DESIGN FOR A DISPENSING CONTAINER
OR SIMILAR ARTICLEBenjamin David Menkin, Los Angeles, Calif., assignor to Menda Company, a corporation of California

Application September 14, 1946, Serial No. 133,321

Term of patent 14 years

(CL. D58—8)

To all whom it may concern:

Be it known that I, Benjamin David Menkin, a citizen of the United States, residing in Los Angeles, in the county of Los Angeles, State of California, have invented a new, original, and ornamental Design for a Dispensing Container or Similar Article, of which the following is a specification, reference being had to the accompanying drawings, forming a part thereof.

The essential features of my design reside in the portions shown in solid lines.

I claim:

The ornamental design for a dispensing container or similar article, as shown and described.

BENJAMIN DAVID MENKIN.
